CLAIM

What is claimed is the ornamental design for a lidar sensor assembly, as shown.

DESCRIPTION

FIG. 1 is a perspective view of a lidar sensor assembly according to a second embodiment;

FIG. 2 is a front elevation view of the lidar sensor assembly shown in FIG. 1;

FIG. 3 is a rear elevation view of the lidar sensor assembly shown in FIG. 1;

FIG. 4 is a left side elevation view of the lidar sensor assembly shown in FIG. 1;

FIG. 5 is a right side elevation view of the lidar sensor assembly shown in FIG. 1;

FIG. 6 is a top plan view of the lidar sensor assembly shown in FIG. 1; and,

FIG. 7 is a bottom plan view of the lidar sensor assembly shown in FIG. 1.

The portions of the lidar sensor assembly shown in broken lines are for illustrative purposes only and form no part of the claimed design.
